UNITED STATES PATENT OFFICE.

JULIUS E. THIELER, OF BROOKLYN, NEW YORK.

SWITCH.

Application filed March 18, 1925. Serial No. 16,530.

This invention relates to improvements in switches and which is of the type broadly mentioned in my co-pending application Sr. No. 3424, filed January 19, 1925.

5 The principal object of the invention resides in a switch for use in connection with a signalling system for motor vehicles and is operatively connected with the foot actuated brake pedal for automatically controlling the operation of the "stop" signal.

Another object of the invention is the provision of a make and break device for respectively releasing a movable drum bearing certain indicia, operating a motor for rotating the drum, for stopping the drum when the desired indicia bearing panel is brought into the proper position, and for illuminating the indicia.

With these and other objects in view, the invention resides in certain novel construction and combination and arrangement of parts, the essential features of which are hereinafter fully described, are particularly pointed out in the appended claim, and are 20 illustrated in the accompanying drawing, in which:—

Figure 1 is a view illustrating my improved switch in applied position upon a portion of a motor vehicle.

30 Figure 2 is a plan view of the switch per se.

Figure 3 is a transverse sectional view on the line 3—3 of Figure 2.

Figure 4 is a longitudinal sectional view 35 on the line 4—4 of Figure 2.

Figure 5 is a diagrammatic view of the switch arranged in a signal circuit.

Figure 6 is an elevational view of the hand 40 operated switch used in connection with my foot actuated switch.

Figure 7 is a horizontal sectional view on the line 7—7 of Figure 6.

Figure 8 is an elevational view of the indicator.

45 Figure 9 is a horizontal sectional view on the line 9—9 of Figure 8.

Figure 10 is a transverse sectional view on the line 10—10 of Figure 8.

Referring now more particularly to the 50 several views of the drawing, it will be apparent that, the indicator of the present invention will include a signal display unit 10, an operator's controlling unit 11, and a foot controlled unit 50. In accordance with the 55 present invention the signal display unit 10 is arranged in a conspicuous place at the battery 29.

rear end of a vehicle for instance, whereas the operator's controlling unit 11 will be arranged at a point remote from the unit 10 such as at a point near the vehicle operator's seat while the unit 50 is disposed beneath the flooring of the vehicle between the chassis frame. The suggestion just made has reference to an automobile, but obviously the indicator may be used or arranged on other types of vehicles such as street cars or wherever signals are to be flashed or displayed.

The signal display unit 10 includes a casing 12 which embodies means for attaching the same, and the said casing has a sight opening 13 in the front wall thereof. Arranged within the casing 12 is a rotatable drum 14 which comprises spiders 15 which support a plurality of signal or indicia bearing panels 16; the spiders 15 being arranged respectively at the opposite ends of said panels. Each spider 15 has a central stub shaft 17 which is journaled in suitable bearings carried respectively by the partition 18 and 75 one end wall 19 of the casing. The stub shaft 17 of one of the spiders 15 has attached thereto a gear 20 with which a gear 21 of the shaft of a motor 22 meshes, so that upon the operation of the motor and by virtue of 80 the intervention of the gears 21 and 20, motion will be imparted to drum 14. The panels 16 of the drum 14 are so disposed that they may be brought selectively into registration with the sight opening 13. There are 85 seven panels in the present instance each of which embodies a certain signal or certain indicia. In the present instance the panels respectively bear the following indicia, 90 namely Stop, Slow, Forward, Pass, Reverse, Left and Right. The words Left and Right are also accompanied with arrows which indicate direction in accord with the word respectively with which they are associated. In order that the desired indicia bearing 95 panel 16 may be brought into registration with the sight opening 13, and further, in order that the particular indicia bearing panel may be illuminated there is provided devices presently described.

100 By referring to the drawings and especially to Figure 5 it will be seen that there is employed a series circuit having a motor 22, contact segment 23, spring actuated pivotally mounted member 24, contacts 25, 26 and 27, an electromagnetic device 28, and 110 a second series circuit is em-

ployed which has thereon lamps 30, contacts 31, and battery 29. The device 28 includes a core 32 which has one end thereof pivotally connected as at 33 to a member 34 pivotally mounted as at 35 to a stationary support 36. The member 34 carries an arresting member 37 and the free end of the member 34 has a contact 38 which is capable of bridging the contacts 31. It will now be manifest that by moving the member 24 so as to bring portions thereof respectively into engagement with the contact 25 and the segment 23 that, among other things the motor 22 will rotate and as a consequence the drum 14 will also be rotated. By employing a rotatable make and break device 39, it is possible to complete the circuit from the battery 29 through member 24, through contacts 25, 26 and 27 to the coil of the device 28 which magnetizes core 32 and causes the same to move into the direction of the arrow thus causing the member 34 to move on its pivot 35 with the result that the member 37 will be moved into engagement with a portion of the related spider 15 and the contact 38 will be moved between the contacts 31 to bridge the same. The free end of the arresting member 37 supports a switch 37' which normally closes the circuit to the motor but which circuit is broken when the member is inserted between legs of the spider at which time the spider operates the switch 37' to break the connection thus shutting off the motor. It will be manifest that by the single manipulation of the member 24 the motor 22 is set in motion to rotate the drum 14 and the device 39, and that such action is followed by the lighting of the lamps 30 and the movement to the member 37 to an obstructing position. By moving the member 24 so as to separate the portions thereof from engagement with the contact 25 and the segment 23, the motor will be stopped and therefore cannot further rotate the drum 14 which is now held against movement aside from its being moved by the motor 22 by the member 37.

Inasmuch as there are seven panels 16 employed each of which bears distinctive indicia there are provided seven of each of the contacts 25, 26 and 27. There are also provided seven contacts 40 as parts of the circuit closing device 39. Each contact 40 is arranged on the cylinder 41 of the device 39 with respect to the arrangement of the particular panels of the drum 14. The cylinder of the circuit closing device is mounted for rotary movement and is connected through a gear train with the motor 22 as clearly shown in Figure 9. In other words, each contact 40 operates in conjunction with the pair of contacts 26 and 27 so that when a particular and desired panel is in registration with the sight opening 13 its corre-

sponding contact 40 will bridge a particular pair of contacts 26 and 27, and due to the fact that a portion of the member 24 is in engagement with a particular contact 25 it is possible to move the obstructing member 37 to engage a portion of the adjacent spider 15 to maintain the proper registration of the intended panels 16. The contacts 27 are connected of course in parallel with the coil of the device 28, whereas the seven contacts 25 are connected respectively to the seven contacts 26. The contacts 26 and 27 are carried by a support 42 arranged in juxtaposition to the device 39 and both the device 39 and support 42 are arranged within the casing 12; the former being rotatably supported in suitable bearings and the latter being held stationary.

In order that the arresting member 37 can be withdrawn from engagement with a portion of the spider 15, and further, in order that the contact 38 may be moved from between the contacts 31 there is provided a series circuit which has therein battery 29, member 24, contact segment 42 and electromagnetic device 43. The core 44 or the device 43 is connected to the member 34. Upon the movement of a portion of the member 24 into engagement with the segment 42 a circuit will be closed through the coil of the device 43 and as a result the core 44 will be moved to its normal position and the member 37 will be in an unobstructing position while the contact 38 will be withdrawn from between the contacts 31. It follows that the lamps 30 will be out and the drum 14 will be free to rotate.

It is to be understood that the devices 28, and 43, and the contacts 31 are arranged within the casing 12, and the lamps 30 are preferably supported by a bar 45 which receives support from the partition 18. The lamps are spaced and lie directly behind the sight opening 13.

The contacts 25 and segments 23 and 42 are embodied by the controlling unit 11 as is the member 24. The arrangement of these parts is such that by one manipulation of the member 24, one of the contacts 25 and the segment 23 may be simultaneously engaged or disengaged and by another manipulation a portion of the member 24 is brought into engagement with the segment 42 for the purpose specified. The member 24 may also be moved to a neutral position.

The foot actuated switch 50 heretofore referred to only broadly comprises a U-shaped supporting bracket 51 within which is supported a block 52 of insulating material and which in turn supports pairs of contacts 53, 54 and 55. Suitable wire connectors 56 are electrically connected to one of each of the sets of contacts 53 and 54 while each contact of the set 55 is provided with a connector. A strip of conducting material 57

connects one contact of the set 53 with a corresponding contact of the adjacent set 54.

A roller 58 of insulating material is journaled in the bracket 51 adjacent the sets of contacts and supports spaced contact plates 59, 60 and 61 for respectively bridging the stationary sets of contacts 53, 54 and 55. A relatively small gear 62 is keyed to the same shaft on which the roller is mounted and is disposed on the outside of the bracket for mesh with a large gear 63 rotatably mounted upon the exterior of the bracket. An arm 64 extends from the gear 63 and has its free end formed with a slot 65 for connection with a pin 66 carried by the rod 67 leading from the brake pedal 68 to the brake drums of the vehicle.

In Figure 5 of the drawings there is shown a diagrammatic view of my improved switch in circuit with a signal device which has been fully set forth and it will be seen that a wire 69 leads from the connector 56 of one of the contacts of the set 53 to the magnet 43 and a wire 69' leads from one of the contacts of the set 54 to one of the contacts 26, while a wire 70 leads from the other contact of the set 54 to a contact 72 in the path of movement of the member 24. A wire 73 leads from one of the contacts 55 to the motor 22 while a wire 74 leads from the other contact of the set 55 to a contact 75 also arranged in the hand switch and which is engaged by the member 24. When the contacts 72 and 75 are bridged by the members 24 the signal is set for operation by the foot actuated switch 50.

When the hand switch is set as just mentioned and the brake pedal 68 depressed, the roller will be rotated through the rod 67, arms 64 and gears 62 and 63. As the roller revolves, the set of contacts 53 are first bridged by the plate 59 which operates the magnet to release the obstruction 37 from between the spokes 15 of the drum. Upon further movement of the roller, the

plate 61 bridges the set of contacts 55 to operate the motor 22 to rotate the drum, after which the plate 60 moves into engagement with the set of contacts 54 which energizes the magnet 28 for extending the obstructing member 37 within the path of movement of the spider 15 thereby bringing the stop signal into registry with the opening in the casing, at which time the switch 31 is closed which lights the lamps 30 and simultaneously breaks the switch 37 which stops the operation of the motor.

When pressure is released from the brake pedal, a spring 76 attached to the large gear 63 and a portion of the bracket returns the roller 58 to normal position.

What is claimed as new is:—

In a vehicle having a foot brake pedal, a motion signal device comprising a drum, means for mounting the drum for rotation about its longitudinal axis, a plurality of translucent motion signal indicia on the surface of the drum, one of the indicia being "Stop", electrically driven means for rotating the drum, an electric lamp positioned within the drum, electromagnetically actuated means for controlling the lamp and for simultaneously arresting the movement of the drum and its driving means in a selected signalling position, means for controlling the arresting means including a selective manual switch and a rotating contact device geared to the drum to cause the latter to be rotated to any selected signalling position, additional means including a switch operated by the brake pedal of the vehicle and the drum operating means for causing the drum to be rotated to the "stop" position only, and circuit means interconnecting the manual switch, the brake actuated switch, and the rotating contact device for rendering the brake operated switch inoperative when the manual switch is in any selected signalling position.

In testimony whereof I have affixed my signature.

JULIUS E. THIELER.
